UNITED STATES PATENT OFFICE.

ROBERT J. MCKAY, OF PITTSBURGH, PENNSYLVANIA.

STAY-BOLT.

1,308,186.

Specification of Letters Patent.

Patented July 1, 1919.

Original application filed May 5, 1915, Serial No. 26,130. Divided and this application filed July 29, 1916.
Serial No. 112,050.

To all whom it may concern:

Be it known that I, ROBERT J. MCKAY, a citizen of the United States, and resident of Pittsburgh, in the county of Allegheny and State of Pennsylvania, have invented a new and useful Improvement in Stay-Bolts; and I do hereby declare the following to be a full, clear, and exact description thereof.

10 My invention relates to stay-bolts.

The invention has relation more particularly to stay-bolts for uniting boiler-plates, such as the outside shell and fire-box shell of locomotives, and to the type described and claimed in Letters Patent of the United States No. 792,863, of June 20, 1905, to George S. Thompson, the distinctive features of which being that the eye-head and eye-bolt are inter-linked by their eye-loops 15 so as to give a certain amount of play while, at the same time, independent rotary movement of the parts is prevented. In an application filed by me on May 5, 1915, Serial No. 26,130, I described and claimed a stay-bolt comprising a shank having a loop, an eye-head having a loop engaging the loop of said shank, said eye-head consisting of an eye-loop portion formed with a longitudinally-divided tail-piece, a projection on said 20 tail-piece, and a cap inclosing said tail-piece and forming an interlocking connection with said projection.

The present invention is included within the scope of the above-named invention, and 25 said present invention relates to a specific form of stay-bolt construction, as herein-after set forth and claimed.

In the accompanying drawing, Figure 1 is a view of my improved stay-bolt, partly 30 broken away; Fig. 2 is a longitudinal section, partly broken away; Fig. 3 is a view of the eye-loop portion of the eye-head; Fig. 4 is a view of the manner in which the eye-loop portion of the eye-head is inserted in 35 the eye-loop of the shank; Fig. 5 is a view of the cap; Fig. 6 is a view before the cap has been closed around the longitudinally divided tail portion; and Fig. 7 is a cross-section on the line 7—7, Fig. 2.

40 The numeral 2 designates the shank or bolt portion which is provided with the loop 3 at one end and the threaded portion 4 at the opposite end.

The eye-head 5 is composed of two parts—namely, the eye-loop portion 6 and the cap 7. 55 The eye-loop portion 6 is first formed in substantially the shape shown in Fig. 3 with the diverging tail-pieces 8. In the present instance, these tail-pieces are formed with the flat faces 9 forming, when the tail-pieces are 60 brought together, a hexagon. One of the tail-pieces is provided with the recessed portion 10 to receive the corresponding tongue-portion 11 to form an interlocking connection between the two sections of the tail-piece when brought together.

The tail-piece is provided with the enlargement 12 forming a hexagon head corresponding to the hexagon formed by the angular faces 9. An additional enlargement 70 12 may be formed on the tail pieces between the enlargement 12 and the loop portion.

To connect the eye-loop portion 6 up with the eye-loop 3 of the shank 2, one of the tail-portions 8 is inserted in the opening of the 75 eye-loop 3 at right angles to the axial line of the shank whereupon the eye-loop portion 6 is turned around to normal position. Pressure is then applied to the tail-portion 8 of the eye-loop portion 6 to force said 80 tail portions into contact, as indicated in Fig. 6, the tongue-portion 11 entering the recess 10 to form an interlocking connection between the parts. It should be mentioned that the eye-loop portion is heated 85 sufficiently to permit of this pressing of the tail-portions 8 into contact. The cap 7 is then fitted over the tail-portion of the eye-head, as indicated in Fig. 6, said cap having the recess 13, said recess being hexagonal 90 in shape to receive the hexagonal enlargement 12 on the tail-piece, as clearly indicated in Figs. 5 and 6. The metal of the cap is then squeezed down around the tail-piece so as to inclose the same, as indicated 95 in Fig. 2, and a very secure inter-locking connection is formed between the cap and said tail-piece due to the enlargement 12 and the hexagon formed on said enlargement as well as the seat formed in the cap. 100

Threads may then be formed in the outer portion of the cap, as indicated in Fig. 2, to provide for the screwing of the eye-head into a threaded opening in the boiler-sheet.

It is to be understood that my invention 105 is not limited to the short stay-bolts used

for uniting the outside sheet and the fire-box sheet of boilers, but it is applicable for use as a stay-rod for connecting the top boiler-sheet with the front or rear boiler-sheet for 5 the radial stays.

What I claim is:

1. A stay-bolt comprising a shank having a loop, an eye-head having an eye-loop engaging the loop of said shank, said eye-head 10 comprising an eye-loop portion formed with a longitudinally-divided tail-piece, an enlargement on said tail-piece, an interlocking connection between said tail-piece portions, and a cap inclosing said tail-piece and 15 engaging said enlargement.
2. A stay-bolt comprising a shank having a loop, an eye-head having an eye-loop engaging the loop of said shank, said eye-head comprising an eye-loop portion formed 20 with a longitudinally-divided tail-piece, an enlargement on said tail-piece, a projection on one of said tail-piece portions adapted to engage a recess formed in the other tail-piece portion, and a cap inclosing said tail-piece and engaging said enlargement. 25
3. A stay-bolt comprising a shank having

a loop, an eye-head having an eye-loop engaging the loop of said shank, said eye-head comprising an eye-loop portion formed with a longitudinally-divided tail-piece, a polygonal enlargement on said tail-piece, and a cap having a correspondingly-shaped recess to receive said enlargement, said cap being bent around said tail-piece to inclose the same. 30

4. A stay-bolt comprising a shank having a loop, an eye-head having an eye-loop engaging the loop of said shank, said eye-head comprising an eye-loop portion formed with a longitudinally-divided tail-piece, said 35 tail-piece being polygonal in form, a polygonal enlargement on said tail-piece, a cap having a correspondingly-shaped recess therein to receive said tail-piece and engaging said enlargement, and said cap bent 40 around to inclose the same. 45

In testimony whereof I the said ROBERT J. McKAY, have hereunto set my hand.

ROBERT J. McKAY.
